Golden Blount, Santa Monica, Calif., assignor to Apsco Products, Inc., Los Angeles, Calif., a corporation of California

Filed Feb. 21, 1966, Ser. No. 1,135

Term of patent 14 years

(Cl. D64—10)

FIG. 1 is a side view of a tape embossing device embodying my new design, the broken lines showing the roll of tape in the handle portion being for illustrative purposes only;

FIG. 2 is a top view thereof;

FIG. 3 is an end view from the left hand end of FIG. 1;

FIG. 4 is a side view taken from the opposite side in relation to FIG. 1;

FIG. 5 is a bottom view of FIG. 4, and

FIG. 6 is an end view from the left hand end of FIG. 4.

The dominant features of the design are shown in full lines.

I claim:

The ornamental design for a tape embossing device, substantially as shown and described.
